(57) **CLAIM**

The ornamental design for a curved body of cheese made of offset curved slices of cheese, as shown and described.

DESCRIPTION

FIG. 1 is a curved body of cheese made of offset curved slices of cheese showing my new design;

FIG. 2 is a front elevational view thereof;

FIG. 3 is a first side elevational view thereof;

FIG. 4 is a rear elevational view thereof;

FIG. 5 is a second side elevational view thereof;

FIG. 6 is a top plan view thereof;

FIG. 7 is a bottom plan view thereof;

FIG. 8 is a second embodiment of a curved body of cheese made of offset curved slices of cheese showing my new design;

FIG. 9 is a third embodiment of a curved body of cheese made of offset curved slices of cheese showing my new design; and,

FIG. 10 is a fourth embodiment of a curved body of cheese made of offset curved slices of cheese showing my new design.
